UNITED STATES PATENT OFFICE

CHARLES E. H. ARMBRUSTER, OF DENVER, COLORADO

DIAGNOSTIC INSTRUMENT

Application filed February 1, 1927. Serial No. 165,140.

This invention relates to diagnostic instruments of the class exemplified by the ophthalmoscope and the retinoscope which are employed in the diagnosis of ocular diseases and the refractive condition of the human eye, and its primary object resides in the provision of certain improvements in the instrument of the above stated class, shown and described in my United States Letters Patent No. 1,692,241 issued November 20, 1928.

An aim of the improvements is simplicity of construction leading to a reduced cost of production and greater practicability in use and another purpose of the improvements is to facilitate the adjustment of the lamp of the instrument relative to the focal point of the therewith cooperative reflector, and to afford ready access to any of the parts of which the instrument is composed.

Further objects of the present invention will be brought out in the course of the following description, with reference to the accompanying drawings in the several views of which like parts are similarly designated and in which

Figure 1 represents an elevation of the instrument,

Figure 2, a longitudinal section on the line 2—2 Figure 1,

Figure 3, an elevation of the lamp unit of the instrument and in fragmentary and partially sectional elevation, the body portion of the casing in which the unit is normally enclosed,

Figure 4, is a sectional elevation of the upper portion of the instrument, drawn to an enlarged scale,

Figure 5, a section along the line 5—5 Figure 4,

Figure 6, a section taken on the line 6—6 Figure 4,

Figure 7, an elevation of the upper portion of the body-portion of the casing of the instrument,

Figure 8, an enlarged section along the line 8—8 Figure 2,

Figure 9, a section taken on the line 9—9 Figure 4, and

Figure 10, a detail view of the lower portion of the staff included in the lamp unit.

Referring further to the drawings, the improved instrument comprises a cylindrical casing composed of a body portion 5 and a therewith telescoping top-section 6. The casing encloses the lamp-unit, the light collector, the lens and other parts of the instrument and its sections are readily pulled apart to expose the lamp for its adjustment, as will hereinafter be more fully described.

The lamp unit hereinbefore referred to consists of a base 7 of non-conductive material which plugs the lower end of the casing, and a standard 8 fastened to the plug and extending lengthwise of the casing along a portion of the inner surface thereof. A resilient blade 9 encased in a sheath 10 of insulating material is fastened to the plug opposite to the standard and terminates in a contact-finger 12 by which in practice the circuit of the lamp is closed. A button 13 connected at the upper end of the blade, extends through registering openings in the two telescoping sections of the casing, to close the circuit by finger-pressure.

Both the standard and the blade are fastened to the plug by means of screws 14 as best shown in Figure 2 and the complete unit is fastened in the casing by two screws 15 which permit of ready removal of the unit after the button has been detached from the contact-blade.

The incandescent lamp 16 of the instrument is screwed into a metal socket 17 which is mounted on a block 18 of insulating material.

The terminal at the end of the lamp-plug contacts with the head of a staff 19 extending through an axial bore of the insulating block and having a collar 20 engaging the lower end of the block. The stem extends downwardly through an axial bore of the insulating plug at the lower end of the casing and its lower portion is screw-threaded for the application of an adjusting nut 21 which engages the end of the plug outside the casing and which extends partially in a countersink of the bore of the plug. The stem which can move lengthwise in the bore of the plug is supported on a coiled spring 22 by means of an enlarged boss 23. The spring is disposed

in an enlargement of the bore of the plug and the boss has a laterally projecting arm 24 best shown in Figure 10, which extends in a recess in the outer surface of the plug to hold the staff against rotation and which is equipped with a binding-screw 25 for the attachment of one of the wires 26 of the plug by means of which the instrument is connected in the circuit.

10 The last mentioned plug has not been shown in the drawings, since its construction is similar to that of plugs of other electrical instruments at present in common use. It is to be understood however that in the conductor by which the plug is connected to the instrument, is included a rheostat of suitable size and form which in the operation of the instrument serves to regulate the intensity of the light beam.

15 20 The other conductor is connected to an arm 27 of the contact blade 9, shown in broken lines in Figure 3.

The staff has immediately above the boss 23, a neck 28 of reduced diameter which permits of its deflection for lateral adjustment by means of screws 29 in threaded openings of bosses of a head 30 on the standard 8.

10 15 20 25 The screws engage with a metal ring 31 around the lower end of the insulating block 30 of the lamp-socket, and a coiled spring 32 stretched against the ring between two hooks on the head of the standard, to which its ends are fastened, tends to hold the ring in constant engagement with the protruding ends 35 of the adjusting screws. The outer ends of the screws which are nicked for the application of a screw driver, are accessible through openings 33 in the body portion of the casing.

10 15 20 25 30 The body portion of the casing has at quadrant points of its upper edge, notches 34 to facilitate "centering" of the lamp.

10 15 20 25 30 35 Clamped between opposite shoulders on the two sections of the casing, is a preferably elliptic focusing reflector 35 which has a central opening through which the lamp protrudes. The reflector directs the light rays emitted from the lamp to a light-transmitting concentrating element located in the focal point of the reflective surface.

10 15 20 25 30 35 The element as shown in the drawings consists of a complete sphere 36 of glass or other suitable transparent material which is supported between two disks 37 provided with central beveled apertures to admit opposite portions of the sphere.

10 15 20 25 30 35 The disks conjointly provide an opaque diaphragm which is supported on a rim at the lower end of a tubular holder 38 and held in place by a split bushing 39 which is fitted 60 in the holder above the diaphragm. The bushing is held inside the holder by the resiliency of the metal of which it is composed and it is readily removed to afford access to the sphere. The holder 38 has an external screw-thread that cooperates with a

corresponding thread in the tubular end portion of the section 6 of the casing for the adjustment of the sphere to its proper position in the focal point of the reflector.

10 15 20 25 30 35 The adjustment of the holder is facilitated by a milled rim above the end of the casing-section in which it is screwed. Slidably fitted upon the tubular end-portion of the casing is a sleeve 40 which at its outer end carries the condensing lens 41 of the instrument. The sleeve has an exterior enlargement for the support of the sight element which comprises a supporting plate 42 fastened to the enlargement by means of screws 43.

10 15 20 25 30 35 40 45 The plate has a sight-opening 44 and in axial alinement therewith, a smaller sight hole 45 at the end of a conical eye-piece 46. A tubular bracket 47 projecting forwardly from the plate carries a slanting annular back 48 for a reflecting mirror 49 which is inclined at an angle of approximately forty-five degrees above the condensing lens.

10 15 20 25 30 35 40 45 50 The mirror has in its silvering an aperture centrally located in the axis of the lens 41, which is coincident with the axes of the lamp-casing and the light condensing sphere, and it is held in place by a frame 51 provided with resilient fingers 52 for its clamping engagement with the rim of the annular back.

10 15 20 25 30 35 40 45 50 55 The axis of the sight-opening coincides with that of the aperture in the mirror and at that point intersects the axis of the condensing lens so that when the lamp is lighted by the completion of its circuit through pressure on the button, the beam of light emanated through the condensing lens and reflected at an angle of about ninety degrees by the slanting mirror, can be directed by the operator looking through the eye-piece, to the eye of the patient.

10 15 20 25 30 35 40 45 50 55 60 The light rays emitted by the lamp are focused by the reflector upon the sphere which thereby becomes a secondary source of light free from shadows or spots ordinarily produced by an image of the lamp filament, the light passing through the condensing lens as a circular beam of high illuminative power.

10 15 20 25 30 35 40 45 50 55 60 65 It is essential that the sphere or other light condensing object be located at the focal point of the reflector and that the filament of the lamp be in the axis of the reflector and so located as to focus its light rays by means of the elliptic reflector directly upon the condensing element. In short, the condensing element and the filament must be so placed in relation to the reflector that the two focal points are in conjugation.

10 15 20 25 30 35 40 45 50 55 60 65 70 The adjustments herein described are therefore of paramount importance, it being evident that the adjustment of the lamp in the axis of the instrument is readily effected by rotation of the nut 21 at the end of the casing, that the lateral adjustment of the lamp relative to the axis of the reflector may 120 125 130

be accurately accomplished by rotation of one or another of the two screws 29 and that the position of the condensing sphere in the axis may be varied by rotation of the holder 38.

5 After the upper section of the casing has been removed the adjustment of the lamp is facilitated by the notches 34 in the upper edge of the body section, which being opposite to each other in lines intersecting at right angles, serve as sights.

10 It is further to be observed that the construction of the instrument permits of ready access to all of its constituent parts. Both 15 the sleeve 40 of the sight plate and the upper section 6 of the casing are removed by a mere sliding movement.

20 The separation of the sections of the casing, exposes the reflector for removal, and by unfastening the two screws 15 and detaching the button 13 the entire lamp unit can be removed from the casing.

25 Having thus described my invention, what I claim and desire to secure by Letters Patent is:—

30 1. In a diagnostic instrument of the character described, a casing, a diaphragm in the casing, composed of spaced disks having central apertures, and a light-condensing sphere 35 clamped between the disks and in the apertures thereof.

35 2. In a diagnostic instrument of the character described, a tubular casing, a holder in the casing, having an inturned rim, a diaphragm on the rim, composed of spaced 40 centrally apertured disks, a light-condensing element between the disks in the apertures thereof, and a resilient bushing in the holder, engaging the diaphragm to hold it in place on the rim.

45 3. In a diagnostic instrument of the character described, a casing, a plug at an end thereof, a lamp-socket in the casing, a staff upon which the socket is mounted, having a screw-threaded end-portion extending through the plug, a spring supporting the staff on the plug, and a nut exteriorly of the plug and 50 cooperating with the screw-threaded portion of the staff for longitudinal adjustment of the same.

55 4. In a diagnostic instrument of the character described, a casing composed of telescoping sections, and a lamp adjustably mounted upon and at the junction between the sections, one of the sections having sight 60 openings at its end adjacent the lamp, to facilitate centering of the lamp by its adjustment.

65 5. In a diagnostic instrument of the character described, a casing, an insulating plug at an end thereof, a standard fastened to the plug, a resilient contact-blade fastened on the plug, a lamp-socket adjustably supported on the plug, means on the standard in 70 operative engagement with the lamp socket

for adjustment of the lamp-socket, and a button exteriorly of the casing to move the blade into contact with the socket.

6 In a diagnostic instrument of the character described, a casing, a plug at an end thereof, a standard fastened on the plug, a lamp socket on the standard, means mounted on the casing for lateral adjustment of the standard and means on the plug for longitudinal adjustment of the same.

7 70 In a diagnostic instrument of the character described, a casing, a diaphragm in the casing composed of spaced members having apertures and a light condensing sphere clamped between the members in alinement with the apertures thereof.

75 8 In a diagnostic instrument of the character described, a reflector adapted to be clamped between telescoping sections, a casing for the instrument composed of telescoping sections having means for clamping the reflector therebetween, the reflector having an opening, an adjustable lamp socket at the opening, a lamp in the socket, and means for adjusting the socket relative to the reflector.

9 90 In a diagnostic instrument of the character described, a casing composed of telescoping sections, said sections having opposed shoulders, a reflector having a projecting portion adapted to be clamped between 95 said shoulders.

In testimony whereof I have affixed my signature.

CHARLES E. H. ARMBRUSTER.
